I. STERN

DENTURE ATTACHMENT

Filed April 2, 1924

INVENTOR

Isidore Stern

UNITED STATES PATENT OFFICE.

ISIDORE STERN, OF NEW YORK, N. Y.

DENTURE ATTACHMENT.

Application filed April 2, 1924. Serial No. 703,587.

To all whom it may concern:

Be it known that I, ISIDORE STERN, a citizen of the United States, residing at New York, in the county of New York and State of New York, have invented certain new and useful Improvements in Denture Attachments, of which the following is a specification.

This invention relates to dental bridge-work of the removable type and more particularly to improvements in denture attachment anchor heads employed to hold a bridge in position between the pier teeth.

A main object of the invention is to produce bridgework construction, and denture anchor head parts therefor, as improved over the bridge and denture attachment disclosed in my application for patent Serial Number 422,653 and Patent 1,451,718.

A further object of the invention is to produce an improved bridgework anchor head or denture attachment possessing a construction which provides inherent strength and at the same time affords flexible spring pressing and yieldable wings which engage pier teeth sockets for the purpose of holding bridges in position.

The construction of the denture attachment may be varied in certain particulars without departing from the socket of the present invention; and the accompanying drawings illustrate a preferred form thereof.

Figure 1 shows an assembly view of the bridge and pier teeth embodying the present improvements.

Figure 2 illustrates a cluster projection of the denture attachment showing the top, rear and side views thereof.

Figure 3 shows an enlarged perspective view of the denture attachment.

Referring now more in particular to the drawings for a detailed description of the invention, there is shown a bridge B interposed between the pier teeth 5; and the pier teeth are usually provided with inlays 6 which carry sockets 7 for the reception of the adjustable anchor head forming an integral part of the bridge B. The bridge B may be removed at any time for the purpose of cleaning the parts and making a readjustment thereof for the purpose of tightening the bridge to improve its function.

Referring to the detailed views of the den-

ture anchor head itself, there is shown an anchor head consisting of a shank part 9 which is cut off to any desired length and joined to the bridge B as shown in an assembly view. The shank 9 carries a head plate which thus forms a substantially T-shaped denture head as illustrated; and the said denture attachment is provided with one or more planes of separation or cleavage for the reception of an opening or spreading tool whereby spring wings, as will be explained, are opened up to improve the fit of the denture attachment in the socket.

A head plate 10 is made substantially rectangular and flat on the front and rear surfaces thereof, and the lower end is preferably tapered slightly to enable the part to be quickly inserted in the socket. The head piece 10 is tapered on the front side thereof beginning at a point slightly from the center and extending towards each end which provides the front tapered surfaces 11. This construction affords a central region 12 of substantial mass or thickness where the parts 9 and 10 are joined, and it is to be appreciated therefore that this denture attachment possesses more strength and rigidity by reason of the fact that the parts 9 and 10 are substantially solid where they are joined, and this is a very desirable feature in removable adjustable denture attachments for the reason that they are subjected to rather hard usage inasmuch as the wearer often removes them for the purpose of adjustment, and inasmuch as the user does not always fully understand the technique and care involved in making the adjustment, it follows that the denture is subjected to unnecessarily hard usage when possessed of a structure susceptible to the adjustment by the user himself.

Tapered wings 14 have their outer thick or heavier margins integrally joined to the outer thin tapered edges of the head part 10; and holes 15 may run through the part from top to bottom to set off and define the point of joinder between the wings 14 and the head part 12. A plane of cleavage or separation is provided between the flexible wings 14 and the main body of the head 10 for the reception of a spreading tool such as a knife edge by which the wings 14 are flexed outwardly. The construction of the head part 10 and 14 is such that the tapered

- wings 14 fill in and lap back upon the tapered body 10 thereby replacing that portion of the metal as removed when the head part 10 was tapered from the central portion towards the edge thereof. This arrangement and structure affords a head 10 which is substantially rectangular in cross section, yet at the same time provides the tapered wings integrally formed therewith.
- 10 The plane of cleavage which separates the head 10 from the wings 14 extends into the openings 15 and inasmuch as each hole 15 is worked out substantially close to the outer wall of the wing and head, it follows that
- 15 the said hole 15 increases the flexible tractor inherent in the spring wing.

The device as described is very strong and durable and is capable of very delicate adjustment, and continued long-period adjustment and use will not impair the strength of the part 9 connected or built onto the head part 10.

What I claim is:

1. In combination, dental bridgework comprising a pier tooth member provided with a socket, a bridge disposed adjacent the pier tooth, a shank integral with the bridge and reaching toward the pier tooth socket, a rectangular-shaped head made on the shank 25 and slidably confined in the head, said head having a cleavage plane made to either side thereof which provides flexible pressure wings bearing against the socket wall, the said wings having their adjacent edges spaced apart substantially equal in distance to the thickness of the shank thereby forming a heavy thick body portion at the junction of the head and shank, and the said head joined to the shank along a central 30 line at the heavy body portion thereof between the said adjacent edges of the wings.
2. In combination, dental bridgework comprising a pier tooth member provided with a socket, a bridge disposed adjacent the pier tooth, a shank integral with the bridge and reaching toward the pier tooth socket, a rectangular-shaped head made on the shank forming a T-shaped anchor head adapted to fit in the socket, the said T-head 35 having each outer end thereof tapered and thus providing a central heavy body portion in the head, a tapered flexible spring pressure wing integrally joined to the T-head at each outer tapered end thereof which fills in the tapered portion and provides a substantially rectangular-shaped head, said wings having each inner edge thereof terminated adjacent the central heavy body portion of the head, and said head having 40 an adjustment plane of cleavage or separation provided between each wing and the T-head anchor part for expanding the wing tips outwardly away from the central heavy body portion to increase the pressure exerted thereby against the socket walls.

3. A denture anchor head comprising a flat rectangular head piece shaped down from the center to form parallel edges tapered in cross section and leaving the central part thereof substantially heavy, a shank joined to the central heavy portion of the head piece and providing a T-shaped anchor head, a tapered wing integrally joined to each outer end of the tapered head part and having the free edges thereof lapping back toward the central heavy head part, and said wings adapted to be expanded and press yieldingly.

4. A denture anchor head comprising a flat rectangular head piece shaped down from the center to form parallel edges tapered in cross section and leaving the central part thereof substantially heavy, a shank joined to the central heavy portion of the head piece and providing a T-shaped anchor head, a tapered wing integrally joined to each outer end of the tapered head part and having the free edges thereof lapping back toward the central heavy head part, said wings adapted to be expanded and press yieldingly, and said head provided with an opening near the outer edge thereof running longitudinally through the part and adapted to impart flexibility to the wings.

5. A denture anchor head comprising a flat rectangular head piece shaped down from the center to form edges tapered in cross section and leaving the central part thereof substantially heavy, a shank joined to the central heavy portion of the head piece and providing a T-shaped anchor head, a tapered wing integrally joined to each outer end of the tapered head part and having the free edges thereof lapping back toward the central heavy head part forming parallel front and back surfaces, said wings adapted to be expanded and press yieldingly, said head provided with an opening near each outer edge thereof running longitudinally through the part and adapted to impart flexibility to the wings, and said head piece provided with a plane of cleavage or separation setting off each wing and extending to the opening in which a tool may be inserted to spread the wings.

6. A denture attachment comprising a shank piece by which the device is fastened to a bridge, a flat plate head piece made on one end of the shank, one face of the head piece being shaped down from the region of the shank joinder to each outer edge thereof forming a taper, a tapered wing having its outer thicker wing edge joined to the outer thin head edge and lapping back along the tapering head wall to provide a head piece substantially rectangular in cross section.

7. A denture attachment comprising a shank piece by which the device is fastened to a bridge, a flat plate head piece made on one end of the shank, one face of the head

piece being shaped down from the region of the shank joinder to each outer edge thereof forming a taper, tapered wing having its outer thicker wing edge joined to the outer thin head edge and having its tapered shape lapping back along the tapered wall to provide front and back parallel head faces, and

said denture provided with a plane of separation between the wings and the head part by which the wings are spread to adjust the 10 denture.

In testimony whereof I affix my signature.

ISIDORE STERN.
